UNITED STATES PATENT OFFICE.

PATRICK J. MADIGAN AND JAMES REHAK, OF CHICAGO, ILLINOIS; SAID REHAK
ASSIGNOR TO SAID MADIGAN.

COMBINED FACING-TABLE AND POSTMARKING-MACHINE.

1,072,388.

Specification of Letters Patent.

Patented Sept. 2, 1913.

Application filed June 3, 1913. Serial No. 701,301.

To all whom it may concern:

Be it known that we, PATRICK J. MADIGAN and JAMES REHAK, citizens of the United States, residing at Chicago, in the county of Cook and State of Illinois, have invented certain new and useful Improvements in Combined Facing-Tables and Postmarking-Machines, of which the following is a description, reference being had to the accompanying drawings, forming a part of this specification, in which corresponding numerals of reference in the different figures indicate like parts.

The object of our invention, stated generally, is to provide simple, cheap and effective means for delivering mail matter from a sorting or "facing" table directly to a canceling or post-marking machine.

A further object is to provide automatic means to be located between the facing table and the printing die of the canceling machine or the feed mechanism which delivers the mail-pieces directly to said die, which shall so act upon said mail pieces that such of them as may be delivered at a rate per given unit of time above a given maximum to be determined by the capacity of the marking die, may be temporarily withheld at a predetermined point or stage in their passage, to be successively advanced therefrom at such a rate as will enable them to be properly received and marked by the die, while all of such pieces as may be delivered at said point of detention at a rate not exceeding the capacity of the die may be caused to pass directly past said detaining point to the said die without detention, thereby providing for all irregularities in rate of delivery from the facing table, avoiding clogging and consequent stoppage of the machine and enabling the marking die to be utilized to its full capacity, all of which is hereinafter more particularly described and definitely set forth in the claims.

In the drawings, Figure 1 is a plan view of a portion of a facing table with a conveyer, retarding and separating means, Fig. 2 is a continuation of the view shown in Fig. 1, showing a marking couple and the intervening mechanism forming the mail-piece path and means for temporarily detaining excess quantities of mail, Fig. 3, is a vertical sectional view taken upon the line 3—3, Fig. 1, viewed in the direction of the arrows there shown, Fig. 4, is a like sectional view

taken upon the line 4—4, Fig. 2, viewed in the direction of the arrows there shown, and Fig. 5 is a plan view corresponding to that shown in Fig. 2, except that certain of the parts are shown in relatively different positions.

Various attempts have heretofore been made to feed mail matter directly from a facing-table to a canceling machine, but so far as we are aware, without success. The usual practice is to dump the mail indiscriminately upon the facing-table, when the operatives stationed beside it select the pieces and drop them singly or in bunches edgewise and properly "faced" upon a conveyer by which they are passed through a separating device and thence conveyed to an automatic bunching or stacking mechanism. The pieces so bunched are then transferred by hand to a canceling machine. This hand transfer has been found necessary because of the great irregularity of delivery from the facing table, the average output from which is intended to be equal to or slightly less than the maximum capacity of the canceling machine. It frequently happens, however, that mail is previously faced by the sender and delivered in bunches to the facing-tables, which bunches are dropped bodily by the operators upon the conveyer and often several of such bunches are dropped simultaneously or substantially so. It is obvious, therefore, that in order to avoid congestion in the conjoint use of a facing-table and canceling machine, and to work the latter to its full capacity, provision should be made for taking care of the momentary excess in such a manner as to cause the pieces to be fed to the die in regular orderly succession. This result may be fully accomplished by means of the following described mechanism.

Referring to the drawings, 1, Figs. 1 and 3, designates a portion of a facing-table having the usual conveying chute or runway 2, along the edge provided with a horizontal conveyer-belt 3. The facing table is usually made of a length sufficient to accommodate about eight operatives upon the side upon which the mail-chute is located, the end of said table proper being designated by 4, Figs. 1 and 3. The chute or runway is extended beyond the end of the facing-table, the upper surface of the conveyer belt 3, being upon a level, or substantially so with

an extension or table 5, which forms in a well known way, not shown, a support for one of the pulleys 5^a of said conveyer. In the example illustrated the table of the ceiling machine is shown as forming a part of said extension although it is obvious that it may be detachable therefrom provided it is upon the same level. Upon the outer edge of the runway 2, and extending upwardly 5 therefrom is a wall 6, to the inner face of which, near the delivery end of the facing-table, is attached a light guide-spring 7, Fig. 1, which is diagonally extended across the runway preferably into contact with the opposite wall, to direct the mail-pieces against or close to said wall for the purpose herein-after stated. A plurality or series of retarding fingers 8, 9 and 10, Figs. 1 and 3, are extended through openings in the wall 6, and arranged diagonally across the mail-piece path. Said fingers are pivoted upon vertical axes outside of said wall at 11, 12 and 13 respectively and each is yieldingly held in a normal position as shown by means 10 of a spring 14, one end of which is attached to a stationary stud 15 and the other to an arm 16, rigidly attached to the finger and extending radially from its axis. The finger 8, is, by preference, slightly curved as shown 15 and each of the fingers 9, and 10, is provided with a tip 17, of india rubber or other frictional material. Upon the opposite side of the runway from the retarding fingers and substantially parallel to the main portion 20 of the wall 6, is a feed belt 18, mounted upon pulleys 19, and 20, having vertical axes and adapted to be driven in any well known way. Interposed between the pulleys 19 and 20, and located opposite to the finger 10, is a feed roller 21, the peripheral surface of which is substantially flush with the feed-belt surface, said feed-roller having a rubber or other frictional surface. A guard or shield 22, is extended from the 25 end of the table 1, along that side of the runway upon which the belt 18, is located and is provided with openings for the reception of the pulleys 19 and 20, one of which openings 23 is shown in Fig. 3.

30 The wall or shield 6, is bent inwardly and obliquely to the plane of the feed belt 18, as shown at 24, Fig. 1, from whence it is again extended in a line parallel or nearly so, to the guard 22, so as to leave a relatively narrow pathway between them. A bracket 25, Figs. 1 and 3, has one end rigidly attached to a wall or frame element 26, and is extended diagonally across to the wall opposite to the pulley 20. A separating plate 27, is located between said bracket and a stationary guide-plate 28, arranged parallel thereto, and attached through a slot in the plate 27 to said bracket. The part 27, is extended into the pathway of the mail-pieces 35 and is bent forwardly as shown at 29. A

yielding finger 30, mounted upon the part 27, is also arranged to project into the mail-piece path beneath the part 29. A spring 35 connected at one end to a stationary stud 32, and at the other to the sliding plate 27, 70 is adapted to hold said finger in a normal position, the whole constituting a well known form of separating device for separating the mail-pieces so that they may be thereafter advanced separately. 75

Pivoted mounted upon a vertical driving shaft 33, Figs. 2, 4 and 5, is a yoke 34, having rigidly connected thereto, a swinging arm 35, which is intended to form one wall of a laterally movable guide-way or shifting mail-piece path. The upper end of the shaft is supported by means of a bracket 36, which is rigidly attached to the part 5. The shaft 33 may be driven from any approved source of power. Rigidly mounted upon said shaft is a pulley 37, Fig. 4, which is interposed between feed-rollers 38, having the usual friction surface. Brackets 39, are rigidly attached to the rear face of the arm 35, and form bearings for the shaft of a pulley 40. Curved wings 41 are rigidly attached to said pulley shaft above and below said pulley. A belt 42, is mounted upon the pulleys 37 and 40, being extended through openings 43 and 44, in the arm 35, so as to carry said belt back of the arm. A bracket 45 is rigidly attached to the back of said arm, said bracket being provided with adjustable studs 46, having idle rollers 47—48, mounted thereon over which said belt is trained. The purpose of this construction is to guide the belt out of the mail-piece path while utilizing it to drive the pulley 40 and rotary wings 41. A feed roller 49, Fig. 2, is arranged to act in conjunction with the feed rollers 38. We prefer to make the distance between the pulley-wheel 20 and the feed roller 49, less than the length of the shortest mail-piece in order that the forward end of a mail-piece in passing may be grasped between the rollers 49 and 38, before being released from the feeding action of the belt 18, although the momentum of the moving mail-piece is usually sufficient to carry it a much farther distance. 100

105 A pulley 50, Fig. 2, is mounted upon a vertical shaft 51, adapted to be driven from any suitable source of power, not shown. Pivoted upon said shaft is a swinging arm 52, which is slidably supported upon the flat surface of the table and held in a normal position against an adjustable stop 53, by means of a cord 54 and weight 55, said cord being attached to said bar and trained over a pulley 56, supported in a well known way upon the frame. A belt-pulley 57, is mounted loosely upon a stud 58 upon the free end of the arm 52. A feed belt 59, is trained upon the pulleys 50 and 57, the inner por- 110

tion of which, next to the mail-piece path, is reinforced by means of a backing-plate 60, rigidly attached to the arm 52. A link 61, has one end jointedly connected to the bottom face of the arm 52, as indicated in dotted lines and the other to a lug upon the lower edge of the arm 35, at 62, said link being located in a curved slot in the table so as to present no obstruction in the mail-piece path. The object of said link is to cause both arms to swing in unison for the purpose hereinafter set forth.

A plurality of light flat springs 63, are attached to the inner face of the arm 35, and extended obliquely across the mail-piece path into loose contact with the surface of the feed-belt 59, the purpose thereof being to hold the passing mail-pieces against the belt surface and thereby insure a continuance of the separation caused by the separating mechanism above described. It will be noted that the arm 35 is bent about midway between its ends so as to insure a laterally divergent pathway for the mail pieces which, when the arm is in a normal position, again leads back into substantial alignment with the original pathway. The free end of said arm is provided with an inwardly bent yielding rubber tip 64, and a flexible metal extension 65, as an aid to the separation of the mail-pieces. A short, wide, horizontal conveyer belt 66, Figs. 2, 4 and 5, is mounted upon pulleys 67, beneath the frame with the top level of which the upper surface of said belt is substantially flush. Said conveyer belt is arranged to extend from the end of the feed belt 59, to the end of the arm 35, while its width conforms substantially to the extent of lateral movement of said arm.

A stationary shield 67, is located above one edge of the belt 66 between the pulley 57, and a pulley 68. A feed-belt 69, is trained upon the pulley 68, and a like pulley 70, one of which is connected with a source of power in a well known way. A feed roller 71, of the usual type, is located between the pulleys 68 and 70, substantially opposite to the end of the swinging arm 35. A separating mechanism of any well known type is also located opposite to said feed-roller. In the example illustrated it is shown to comprise the following elements. A transverse vertical shield or plate 72, is rigidly attached to the table. A slidable separator-plate 73, bent laterally at its forward end into parallelism with the feed-belt 69, as shown at 74, is guided between the plate 72 and a stationary plate 75, and rigidly held in a normal position by means of a spring 76, one end of which is attached to a stud 77 upon the stationary plate 75, and the other to a stud 78 upon the sliding element 73. A printing couple

comprising a marking die 79 and an impression roller 80, is located in operative proximity to the feeding belt 69.

It is desirable that the mail-pieces should, after leaving the facing table, be advanced at an accelerating speed for the purpose of establishing relations adapted to permit of their orderly advancement to the die; and while we do not wish to be limited to any specific rates of speed, we would recommend in practice that the speed of the feed-roller 21, be increased about fifty per cent. above that of the conveyer-belt 3; that the peripheral speed of the feed-rollers 38 and 49, and the speed of the belt 59, be increased about seventy-five per cent. and that of the conveyer belt 66, and stacker members 41, about one hundred per cent. above that of said conveyer 3. The speed of the marking die, as well as that of the feed belt coacting directly therewith should be sufficient to conform to or slightly in excess of the average output of mail-pieces from the facing table.

From the foregoing, it will be seen that the pathway between the table and die is divided into a plurality of stages or sections in which the speed of the conveying mechanism is relatively different; that in the first section being sufficient to provide for the maximum output from the facing-table; that of the second stage being in excess of that in the first and that of the third stage substantially equal to or slightly in excess of the speed necessary to provide for the average output of said facing-table.

The operation of said device is as follows: The faced mail-pieces are dropped into the runway by the operatives in constantly varying quantities and are carried into contact with the spring 7, by which they are guided into contact with the feed-belt 18. As they are further advanced they are brought successively into contact with the retarding fingers 8, 9 and 10, which not only serve to press the pieces next to the belt into frictional contact therewith, while retarding the others, but the increased speed of the belt serves to cause a rapid advancement of those next to it so that the tendency is to cause said mail-pieces to be forwarded in single file, one after the other. Should any be found to overlap each other, upon reaching the separating finger 29, they will be completely separated thereby. The conveyer belt 3, is extended nearly to the feed rollers 38, and 49, to which the mail-pieces are thereby conveyed. The advance mail-piece is then caught by said feed-rollers and carried on at an accelerated speed and is pressed by the fingers 63, against the feed-belt 59. The pieces are then conveyed one by one to the conveyer belt 66 and brought into contact with the revoluble wings 41 and pushed laterally thereby against the

feed-belt 69 and into the throat of the separator, from whence they are advanced to the marking die. When the mail pieces are delivered from the facing table at a lesser rate than or not exceeding the capacity of the die, they will be caused to pass directly through from the facing table to said die without interruption other than that from the mechanism described which is necessary to cause them to be moved in proper order of succession, such normal action being illustrated in Fig. 2, in which 81 illustrates the mail pieces. When, however, they are delivered from the facing table in quantities or at a rate in excess of the capacity of the die, the free end of the arm 35, is caused to be moved laterally away from its normal position by the presence of the rapidly accumulating mail-pieces, thereby shunting the same from the normal path into contact with the arresting stop extending laterally from the normal path and causing them to accumulate side-by-side in the manner indicated in Fig. 5. The action of the weight serves to press the free end of the arm or wing 35, against the hindmost mail piece, thereby pressing the foremost ones in the order of succession against the feed mechanism thereby causing them to be fed in regular order to the die at a rate in conformity to its capacity. As soon, however, as the rate of delivery from the facing table diminishes, the arm 35 is gradually restored to its normal position when the operation is continued without detention of any of the mail-pieces.

It will be seen from the foregoing that the fundamental principle involved is the automatic shifting of the mail-piece path as a result of the quantitative fluctuation of the mail-pieces acted upon, so that as soon as the rate of delivery is increased the excess, above a given quantity, will be shunted and temporarily held in position to be advanced in regular order. It will be noted as the mail-piece path is shifted by the movement of the arm 35, the feed-belt 59, is retained in parallelism with it, so that as the mail pieces are advanced each successive one will be delivered upon the same side and adjacent to the one preceding it, thereby avoiding confusion and clogging. The lateral movement of the arm should be sufficient to take care of any temporary increase in delivery.

Having thus described our invention, we claim:

1. The combination with a facing table and a rotary marking die of means for advancing mail-pieces in a normal path from one to the other, a mail-piece stop arranged adjacent to the mail-piece path to temporarily arrest and hold mail-pieces and laterally yielding means forming a part of said advancing means, the latter preceding

said stop for successively shifting mail-pieces out of their normal path and directing them against said stop when advanced thereto in excess of a predetermined normal rate, while successively pressing the advance pieces so arrested into said normal path to be forwarded to said die at a predetermined limited rate.

2. The combination with a facing table and a marking die of means for advancing mail-pieces in a normal path from one to the other, means adjacent to the mail-piece path for temporarily arresting and holding mail-pieces side-by-side against each other, laterally yielding means, forming a part of said advancing means for shifting mail-pieces out of said normal path and preceding said arresting means for successively directing mail pieces against said arresting means to accumulate in a bunch or pack when advanced thereto in excess of a predetermined normal rate, separating means in operative proximity to said pack and means for laterally pressing the foremost mail-piece of said pack with a yielding pressure toward said separating means.

3. The combination with a facing table and a rotary marking die of conveying means having a capacity equal to the maximum capacity of the operatives at the facing table for conveying mail pieces from said facing-table toward said die, separating means, conveying means conforming substantially in speed to the speed of the marking-die for conveying mail-pieces from said separating means to said die, a laterally movable guide-way forming a part of the mail-piece path between said facing table and said separating means and means for yieldingly holding said guide-way in normal registration with said separating means with a yielding pressure to permit a direct continuous passage from the table to the die of all mail-pieces advanced at a given rate per unit of time and to temporarily withhold those which are advanced in quantities in excess of said rate.

4. The combination with a facing table and a rotary marking die of an intermediate mail-piece pathway divided into a plurality of stages or sections, conveying means for moving mail-pieces from said table to the end of the first stage, the capacity of said conveying means being sufficient to provide for the maximum mail delivery from the table thereto at all times, means for shifting the direction of the mail-piece path in the secondary stage whenever the mail pieces are advanced in excess of a given rate, to divert the excess mail-pieces from the normal path into position side-by-side in the order of succession with their forward ends against a stop, conveying means in said second section having a higher rate of speed than that of said

- first section, a mail-piece stop at the end of said second section extending laterally from the normal mail-path, separating means at the end of said second section, means for yieldingly holding said second section in a normal position and means for conveying mail-pieces from said second section to said die at a speed in substantial conformity to the peripheral speed of said die.
10. 5. The combination with a facing table and marking die, of conveying means for conveying mail-pieces in a mail-piece path from one to the other, a laterally movable mail-piece guide-way forming an intermediate part of the mail-piece path between said table and die, and primary and secondary separating means arranged respectively before and after said laterally movable guide-way.
15. 6. The combination with a facing-table and a marking die of primary and secondary separating means interposed between said table and die, the former near the table and the latter near the die conveying means for conveying mail-pieces from said facing-table to said primary separating means, a laterally movable mail-piece guide-way interposed between said primary and secondary separating means, conveying means located in said guideway, means for yieldingly holding the delivery end of said guide-way in operative proximity to said secondary separating means and conveying means for advancing mail-pieces from said secondary separating means to said die.
20. 7. The combination with a facing-table and a marking die, of a mail-piece runway between the two, primary and secondary separating means interposed at predetermined points in said runway, conveying means, laterally movable guiding means forming a part of said runway between said primary and secondary separating means and means for exerting a yielding pressure upon the delivery end of said guide-way to hold it in normal registration with said secondary separating means.
25. 8. The combination with a facing table and a marking die of a mail-piece runway between the two, primary and secondary separating means in said runway, laterally movable guiding means forming a part of said runway between said primary and secondary separating means, means for exerting a yielding pressure upon the delivery end of said guide-way to hold it in normal registration with said secondary separating means and means for advancing said mail-pieces from said secondary separating means.
30. 9. The combination with a facing table and a marking die, of primary and secondary separating means interposed at predetermined points between said table and die, conveying means for conveying mail-pieces from said facing-table to said primary separating means, a laterally movable mail-piece guide-way interposed between said primary and secondary separating means, conveying means located upon one side of said guide-way, means for yieldingly holding the delivery end of said guide-way in operative proximity to said secondary separating means and conveying means for advancing mail-pieces from said secondary separating means to said die.
35. 10. The combination with a facing-table and a marking die, of primary and secondary separating means interposed between said table and die, conveying means for conveying said mail-pieces from said facing-table to said primary separating means, a laterally movable mail-piece guide-way comprising a mail-piece path interposed between said primary and secondary separating means, conveying means located upon one side of said guide-way, said conveying means being laterally movable therewith, a rotary stacking member mounted upon said laterally movable guide-way for pressing mail-pieces forwardly and laterally toward said secondary separating means, means for holding the delivery end of said guide-way in operative proximity to said secondary separating mechanism in yielding opposition to the action of said rotary stacking member and conveying means for advancing mail-pieces from said secondary separating means to said die.
40. 11. The combination with a facing-table and a rotary marking die of primary and secondary separating means interposed between said table and die, conveying means for conveying mail-pieces from said facing-table to said primary separating means at a predetermined rate of speed, a laterally movable mail-piece guide-way comprising a mail-piece path interposed between said primary and secondary separating means, conveying means upon one side of said guideway, said conveying means being caused to run at a higher rate of speed than that preceding it, means for holding the delivery end of said guide-way in operative proximity to said secondary separating means, a rotary stacking member upon the opposite side of said guide-way from that of said conveying means and means for advancing mail-pieces from said secondary separating means to said die, at speed conforming substantially to the peripheral speed of said die.
45. 12. The combination with a facing-table and a marking die, of a mail-piece path running between the two divided into stages or sections, the delivery end of the second section being laterally movable, means for conveying the maximum output of mail-

- pieces from the first to the second section, means for laterally moving the delivery end of said second section for laterally diverging the course of the mail-pieces therein, means upon one side of said second section for accelerating the speed of said mail-pieces therein, means upon the opposite side thereof for retarding mail-pieces to cause separation during advancement, separating means at the delivery end of said second section, means for normally holding the delivery end of said second section in operative proximity to said separating means, arresting means adjacent to said separating means, 10 15 20 25 30 35 40 45 50 55 60 65
- means for normally holding the delivery end of said second section in operative proximity to said separating means, arresting means adjacent to said separating means, a stacking member for shunting the mail-pieces laterally toward said separating means and means for conveying said mail pieces from said separating means to said die.
13. The combination with a facing table and a marking die of conveying means for normally conveying mail-pieces from one to the other in a predetermined pathway, intermediate arresting means adjacent to said pathway, separating means in said pathway adjacent to said arresting means, means for causing a section of said pathway to be laterally shifted by the action of mail pieces when advanced at an abnormal rate to deliver excess mail-pieces against said arresting means, and yielding means for normally maintaining said laterally shiftable section in direct communication with said separating means.
14. The combination with a facing table and a rotary marking die, of separating means preceding said marking die for separating mail-pieces to enable them to be delivered in successive order to the die, conveying means having a capacity equal to the maximum capacity of the operators at the facing table for conveying mail-pieces from said table to said separating means, conveying means conforming substantially in speed to that of the marking-die for conveying mail-pieces from said separating means to said die, said first mentioned conveying means comprising as a part thereof a laterally movable guide-way forming a part of the mail-piece path between said facing table and said separator, and means for holding said guide-way in normal registration with said separating means with a yielding pressure whereby an excessive accumulation of mail-pieces may cause said way to move out of registration with said separating means while permitting the foremost mail-pieces to be successively delivered to said separating mechanism.
15. The combination with a facing table and a rotary marking-die of means for conveying mail-pieces from said table to said die, said means comprising as a part thereof a laterally swinging guide member interposed in the mail-piece path to form a sec-

tion thereof for shunting mail-pieces when delivered in excess of a given rate, arresting means adjacent to said path at the end of said swinging member, separating means in operative proximity to said arresting means, means for yieldingly holding said swinging guide member in a normal position to deliver mail pieces directly to said separating means, and means for advancing said mail-pieces from said separating means to said die at a rate of speed conforming substantially to the peripheral speed of said die. 70 75

16. The combination of a facing table and marking die, of means for conveying mail pieces from said table to said die, said means comprising as a part thereof a laterally swinging guide member interposed in the mail-piece path for shunting mail-pieces when delivered in excess of a given rate, means for maintaining parallelism between said swinging guide member and that portion of the conveying means acting therewith, arresting means adjacent to the mail-piece path at the free end of said swinging member, separating means in operative proximity to said arresting means and means for yieldingly holding said guide-members in a normal position. 80 85 90

17. The combination with a facing-table and a rotary marking-die having a mail conveying path between the two, of conveying means for conveying mail-pieces at a given speed from said table to a given point in said path, a swinging arm interposed in said path at the end of said conveying means for shunting mail-pieces out of the normal path when delivered in excess of a given rate, separate conveying means having a speed greater than that of said above named conveying-means, said separate conveying means being arranged adjacent to said swinging arm, movable supporting means for supporting said separate conveying means, means for maintaining substantial parallelism between said supporting means and said swinging arm, arresting means adjacent to the mail-piece path at the end of said swinging arm, separating means in operative proximity to the free end of said swinging arm, means for yieldingly holding said arm in a normal position and final conveying means conforming substantially in speed to the peripheral speed of said die for conveying mail-pieces from said separating means to said die. 95 100 105 110 115 120

18. The combination with a facing-table and a marking die, of means for conveying mail-pieces in a normal path from said table to said die, intermediate means forming a part of said conveying means for shunting mail-pieces from their normal path when advanced from the table in excess of a given rate, means for temporarily arresting the advance of the pieces so shunted, means for separating said mail-pieces prior to their ar- 125 130

rest, separating means in operative proximity to said arresting means, yielding means for maintaining said shunting means in a normal position, and means for laterally moving said arrested mail-pieces to said separating means.

5 In testimony whereof, we have signed this

specification in the presence of two subscribing witnesses, this first day of June 1912.
